UNITED STATES PATENT OFFICE.

VICTOR LEDOUX, OF NEW BEDFORD, MASSACHUSETTS, ASSIGNEE TO HOPEDALE MANUFACTURING COMPANY, OF MILFORD, MASSACHUSETTS, A CORPORATION OF MASSACHUSETTS.

SHUTTLE.

Application filed September 8, 1919. Serial No. 322,454.

To all whom it may concern:

Be it known that I, VICTOR LEDOUX, a citizen of the United States, residing at New Bedford, in the county of Bristol and State of Massachusetts, have invented certain new and useful Improvements in Shuttles; and I do hereby declare the following to be a full, clear, and exact description of the invention, such as will enable others skilled in the art to which it appertains to make and use the same.

This invention relates to an improvement in self-threading shuttles. The object of the invention is to provide a self-threading shuttle adapted to be easily threaded and in which the thread is thereafter confined within the shuttle in a superior and novel manner during the normal operation of the shuttle to the end that dethreading of the shuttle is minimized.

With this object in view, the invention consists in the shuttle hereinafter described and particularly pointed out in the claims.

In the drawings illustrating the preferred embodiment of the invention, Figure 1 is a perspective of a portion of a shuttle embodying the present invention; Fig. 2 is a plan of the same; Fig. 3 a side elevation; Fig. 4 a section on the line 4—4 of Fig. 3; and Figs. 5 and 6 details showing the shape of the scroll member.

The self-threading shuttle illustrated in the drawings is described as follows: The shuttle body 10 is provided with the usual opening 11 for the reception of the bobbin 12, and with the usual delivery eye 13. The filling or thread is conducted into and through the delivery eye 13 by the improved thread block indicated at 14. The thread block 14 is provided with the usual longitudinal thread passage 15 and with the shield 16 overlapping the beak 17. All of the parts thus far described are well-known and familiar to those skilled in the art and form alone no part of the present invention.

In order to confine the thread within the thread passage 15, an improved thread guard is provided which is described as follows: A sheet metal scroll 20 of material length is interposed in the thread passage 15 and is arranged so that its longitudinal axis coincides substantially with the longitudinal axis of the bobbin. The scroll 20 is soldered to the sides and bottom of the thread passage so as to be securely held therein and to

form part thereof. The free edges 22 and 23 of the scroll overlap and are spaced apart a short distance to form an inlet opening into the interior of the scroll through which the thread may pass into the interior of the scroll. The upper free edge 22 extends downwardly from one wall 18 of the thread passage toward and into a depression 25 formed in the other wall 19 of the thread passage so that an inlet opening is formed between the upper side of the edge 22 and the wall of the depression 25 thus permitting the thread to pass around the end of the edge 22 and between the edges 22, 23 into the interior of the scroll. The lower free edge 23 of the scroll is inclined outwardly in a gradual helical path as shown in dotted lines in Fig. 2 for a purpose to be described.

An upper guard 27 is extended from one wall of the thread passage 15 in the same general direction as the upper free edge 22 of the scroll and serves as a guide or bearing surface for the thread, to direct the same into the inlet opening between the member 22 and the wall of the depression 25.

When the shuttle is to be threaded, the thread extends from the bobbin outwardly over the top of the thread block 14 so that as the shuttle starts on its first pick, the thread is drawn across the guide member 27. The guide member 27 directs the thread downwardly into and through the opening between the upper member 22 of the scroll and the wall of the depression 25. As the shuttle continues on its flight, the natural unwind from the bobbin carries the thread inwardly across the helical edge of the lower member 23 of the scroll so that the thread is in this manner conducted by the edge 23 between the upper and lower edges 22, 23 and into the interior of the scroll. In this position the thread continues during the normal operation of the shuttle.

It will be observed that the thread is confined by the scroll at the lower portion of the longitudinal thread passage 15 and at a point substantially in line with the axis of the bobbin. The cooperation of the upper and lower members 22, 23 of the scroll 20 operates to present an indirect outlet passage to the thread with the result that the tendency of the shuttle to dethread is minimized.

The threading operation is facilitated by the upper guide member 27 whose direction of extension from the one wall 18 of the

thread passage is such as to form a flaring mouth with the other wall thereof so that as the thread passes over the top of the thread block, it is directed down around the 5 end of the upper member 22 of the scroll.

The important feature of the invention resides in the provision of the improved scroll in the longitudinal thread passage whereby the thread is successfully confined in an 10 operative position therein during the normal operation of the shuttle. The particular arrangement of the free edges of the scroll aids materially in the ease of the threading operation.

15 Having thus described the invention, what is claimed is:

1. A thread block for self-threading shuttles having, in combination, a longitudinal thread passage, means for guiding 20 the thread to the delivery eye of the shuttle, and a scroll in the longitudinal thread passage in substantial alignment with the axis of the bobbin comprising a band of material length having its upper side edge overlapping the lower side edge and spaced a short 25 distance therefrom, and a guard overhanging said upper side edge and extended downwardly from one wall of the thread passage in the same direction as said upper side 30 edge of the scroll, whereby during the threading operation the thread is guided downwardly and caused to pass around the upper side edge and thence over the lower side edge into the scroll.

2. A thread block for self-threading 35 shuttles having, in combination, a longitudinal thread passage, means for guiding the thread to the delivery eye of the shuttle, and a scroll within the thread passage in substantial alignment with the axis of the 40 bobbin, said scroll comprising a band of material length having its upper side edge overlapping the lower side edge and spaced a short distance therefrom, the edges being arranged to extend in a gradual helical path 45 from the inner end of the scroll upwardly and outwardly therealong whereby during the threading operation of the shuttle the thread is guided by said helical lower edge 50 into the scroll.

3. A thread block for self-threading shuttles having, in combination, a longitudinal thread passage provided with a recess in one wall, means for guiding the 55 thread to the delivery eye of the shuttle, and a scroll within the longitudinal thread passage and in substantial alignment with the axis of the bobbin, said scroll having its upper edge extending downwardly into the recess of the thread passage to form a narrow inlet therewith and having its lower edge extended beneath the upper edge in a helical path toward the other wall of the thread passage whereby during the threading operation the thread is guided by said 60 lower edge into the scroll.

VICTOR LEDOUX.
